STONE POLISHING MACHINE

Charles S. Cushman, Barre, Vt., assignor to Charles S. Cushman, Paul G. Cushman, and Victor Tamborini, copartners, doing business under the name of The Cushman Company, Barre, Vt.

Application February 9, 1949, Serial No. 75,343

8 Claims. (Cl. 51—126)

1

This invention relates to improvements in stone polishing machines and particularly the type of machine disclosed in my prior Patent No. 2,055,404 issued September 22, 1936.

It is old and well known in the art to make polishing machines with a longitudinal movable supporting beam, one end of the beam carrying the grinding or finishing wheel and a driving motor for the wheel mounted on the other end. The supporting beam is suspended from a pivotally mounted trolley and has mechanism for longitudinally shifting the beam with respect to the trolley to unbalance the ends of the beam to adjust the pressure of the grinding wheel on the bed of stone being polished. In machines of this character the operator manually swings the supporting beam in a lateral or sidewise direction to move the grinding wheel over the area of the stone to be polished. As the size of the grinding wheel increases the manual shifting of the supporting beam becomes more difficult due to the increase in the weight of the beam. At the present time the size of the grinding wheel is limited by the physical ability of the operator to manually shift the supporting beam.

It is the primary object of the present invention to provide power mechanism for shifting the grinding wheel supporting beam laterally of the bed of stone being polished without any manual work on the part of the operator thus permitting the use of grinding stones of very large sizes.

A further object of the invention resides in providing a movable crane mounted for longitudinal movement of the supporting beam for the grinding wheel carrying power mechanism for laterally swinging the supporting beam in a horizontal plane.

A still further object of the invention resides in providing a movable crane having power mechanism for laterally shifting the supporting beam of the grinding wheel and a movable power hoist carried by the crane for raising and lowering the supporting beam and grinding wheel.

Another object of the invention resides in providing mechanism of the character described which is simple and durable in construction, reliable and efficient in operation and inexpensive to manufacture.

Other objects and advantages of the invention will be apparent during the course of the following description.

In the accompanying drawing forming a part of this specification and in which like numerals are employed to designate like parts throughout the same,

2

Fig. 1 is a front elevational view of the improved mechanism,

Fig. 2 is a detail top plan view of the power means for the shifting mechanism,

Fig. 3 is a detail front elevational view of the supporting beam for the grinding wheel showing the connections between the shifting mechanism and supporting beam, and,

Fig. 4 is a top plan view of the detail shown in Fig. 3.

Referring to the drawings wherein for the purpose of illustration a preferred embodiment of the invention is shown, the numeral 5 denotes the supporting beam for the grinding wheel 6 which is attached to a vertical shaft 7 journaled in one end of the beam. The driving means for the shaft 7 is similar to the driving means shown in my prior Patent 2,055,404, and as disclosed in my prior patent mechanism for moving the supporting beam longitudinally with respect to its support is provided to unbalance the beam and adjust the pressure of the grinding wheel on the bed of stone being polished. Polishing machines of this class are old and well known in the art and the present invention relates to improvements for use with machines of this general type when made in large sizes.

The improvement comprises a traveling crane generally designated at 8 which is U-shape with a horizontal member 9 formed of spaced channel irons and vertical side members 10 formed of spaced angle irons. The horizontal member 9 at each end is suspended by trolley wheels 11 which ride on the lower flanges of I beams 12 attached to a fixed frame 13. The I beams 12 extend longitudinally of the polishing machine and have their rear ends supported by a frame similar to the frame 13. The crane 8 by reason of the trolley wheels is movable longitudinally of the beams 12 with the side members 10 disposed on opposite sides of the supporting beam 5 of the polishing machine.

Mounted intermediate the ends of the horizontal member 9 and between the channel members thereof is a drum 14 mounted on a shaft 15 journaled in bearings 16 attached to the channel members. An auxiliary frame 17 is attached to member 9 and surrounds the drum 14. An electric reversible motor 18 is mounted on the frame and by means of a belt 19 drives the reduction gearing in housing 20 connected with the shaft 15 through driven gears 21 and 22. A cable is wound on the drum 14 with its ends 23 and 24 extending in opposite directions, so that when 55 one of the ends is being wound on the drum the

other end is unwinding. The ends of the cable are trained over sheaves 25 mounted at each end of member 9 and then pass down between the angle irons of side members 10 around the adjustable sheaves 26 at the lower ends of the side members. The adjustable sheaves 26 are held in the slots formed by the spaced angle irons by bolts 27 and are movable vertically of the side members to adjust their position with respect to the beam 5 of the polishing machine. The end 10 23 of the cable is attached to a bolt 28 slidably mounted in an angle bracket 29 mounted on beam 5. A coil spring 30 is mounted on bolt 28 between the bracket 29 and nut 31 on the end of the bolt to provide a yieldable connection between the cable and beam which absorbs the shock when the cable pulls on the beam. The end 24 of the cable is attached to a take-up drum 32 mounted in arms 33, 34 attached to the beam 5 opposite the bracket 29. A ratchet wheel 35 is attached to 15 one end of drum 32 which is engaged by a pawl 36 pivotally mounted on arm 34. A crank 37 attached to the shaft of drum 32 provides manual means for turning the drum to wind the cable thereon to take up the slack in the cable and 20 tighten the same.

As shown in Fig. 1 a movable carrier 38 is suspended from the member 9 by trolley wheels 39 which ride on the flanges of the channel irons. The carrier 38 is freely movable longitudinally of the member 9 and supports a conventional motor operated chain hoist 40 having its grab hook 41 connected to a flange plate 42 attached to the beam 5 of the polishing machine. The hoist operates to raise and lower the beam 5 and grinding wheel 6.

In operation, when the beam 5 is moved longitudinally relative to its supporting trolley, the pressure of the polishing wheel on the bed of stone to be polished is adjusted. As the beam 5 moves forward or backward relative to its support the crane 8 will also move forward or backward along its supporting beams 12. The motor 18 and motor of the chain hoist 40 are controlled by switches interposed in the circuits of the motors. When it is desired to shift the beam 5 laterally of the bed of stone the operator closes the switch controlling the motor 18 which rotates drum 14 to wind and unwind the ends 23 and 24 of the cable wound thereon. The motor 18 is reversible to rotate the drum in either direction and when the drum is rotated it pulls on either the end 23 to swing the beam 5 to the left or the end 24 to swing the beam to the right. The shock of the pull on the beam is absorbed by the spring 30 of the yieldable connection between the end 23 and the beam. Any slack in the cable between the drum 14 and beam may be taken up by winding the end 24 on the take-up drum 32. As the beam 5 swings to the right or left the chain hoist 40 attached to the beam by grab hook 41 moves with the beam as the carrier 38 is freely movable on the horizontal beam 9 of the crane 8. When it is desired to raise or lower the beam 5 the motor of the chain hoist is operated. Thus it is seen I have provided power mechanism for laterally shifting and raising and lowering the supporting beam which carries the grinding or finishing wheels, permitting the use of much larger grinding wheels.

It is to be understood that the form of my invention herein shown and described is a preferred example of the same and changes in the shape, size and arrangement of the parts may be made

5 without departing from the spirit of the invention or scope of the subjoined claims.

Having thus described my invention, I claim:

1. A stone polishing machine comprising a longitudinal movable and swinging beam, a polishing wheel mounted on one end of said beam, a traveling crane mounted above said beam for free longitudinal movement thereof including a horizontal member having depending side arms on opposite sides of said beam, guide sheaves mounted in the horizontal member and side arms of said crane, a flexible cable trained around said sheaves having its ends connected to opposite sides of said beam, power means carried by said crane operably connected to said cable for pulling said cable in opposite directions to swing said beam in a horizontal plane, and a power hoist movably mounted on the horizontal member of said crane and connected to said beam for raising and lowering the same.

2. A machine of the character described in claim 1 including a yieldable connection between one end of said cable and said beam.

3. A machine of the character described in claim 1 including a take-up drum carried by said beam to which one end of said cable is attached.

4. A stone polishing machine comprising a longitudinal movable and swinging beam, a polishing wheel mounted on one end of said beam, a frame straddling said beam, spaced longitudinal rails carried by said frame, an inverted U-shaped frame suspended from said rails and movable longitudinally thereof, the side arms of said U-shaped frame being disposed on opposite sides of said beam, a flexible cable having its ends connected to opposite sides of said beam, guide sheaves mounted in said U-shaped frame around which said flexible cable is trained, and power means operably connected to said flexible cable for pulling said flexible cable in opposite directions to swing said beam in a horizontal plane.

5. A stone polishing machine comprising a longitudinally movable and swingably mounted beam, a polishing wheel mounted on a spindle journaled in bearings on one end of said beam, a crane including a horizontal member having rigid depending side members at each end rigidly connected to said horizontal member, means suspending said crane above said beam for free longitudinal movement thereof with the side members disposed on opposite sides of the beam in spaced relation thereto, draft means connected to opposite sides of said beam adjacent the end supporting said polishing wheel and extending to the side members of said crane, and power means connected to said draft means to swing said beam in a horizontal plane in opposite directions.

6. A machine of the character described in claim 5 including a power hoist mounted for longitudinal movement on the horizontal member of said crane and connected to said beam for raising and lowering the same.

7. A stone polishing machine comprising a longitudinally movable and swingably mounted beam, a polishing wheel mounted on a spindle journaled in bearings on one end of said beam, a crane including a horizontal member having rigid depending side members at each end rigidly connected to said horizontal member, means suspending said crane above said beam for free longitudinal movement thereof with said side members disposed on opposite sides of said beam in spaced relation thereto, a flexible cable having its ends connected to opposite sides of said beam

and extending to the side members of said crane, a yieldable connection between one end of said cable and said beam, and power means connected to said cable to swing said beam in a horizontal plane in opposite directions.

8. A machine of the character described in claim 7 including a take-up drum mounted on said beam on which the opposite end of said cable is wound.
